[57] ABSTRACT

An automatic doffing apparatus adapted for use with a spinning machine comprises a yarn cutting mechanism, which serves to cut the spun yarn prior to doffing and includes a stationary divergent yarn guide disposed in the vicinity of a cutter section of the cutting mechanism. The yarn guide is formed with a yarn restraining part in side by side relation with the blades of the cutter in a yarn cutting position thereof. A device for biasing the yarn into a fixed position, i.e., into the said yarn restraining part of the yarn guide includes a pair of yarn biasing members operable to open and close to thereby positively direct the yarn into the yarn restraining part of the yarn guide.

FIG. 3

DEVICE FOR BIASING YARN INTO FIXED POSITION FOR USE WITH YARN CUTTING MECHANISM OF AUTOMATIC DOFFING APPARATUS

BACKGROUND OF THE INVENTION

This invention relates to an automatic doffing apparatus adapted for use with spinning machineries where doffing of cheeses or packages is necessarily effected, such for example as, an open end spinning machine, a cheese winding machine, and the like and more particularly to a yarn cutting mechanism of the doffing apparatus provided with a device for biasing a spun yarn into a fixed position, prior to its being cut for doffing full packages.

For example, an automatic doffing apparatus, mounted on an open end spinning machine to move along the front thereof, is adapted to demount full bobbins or packages from bobbin holders and to apply empty bobbins to the bobbin holders, from which the full packages have been doffed. Prior to doffing the packages, it is of course necessary to cut the respective yarns. This must be done in a very short time by reason that, when cutting the yarn, it is being taken up while making a traverse motion to form the package and the doffing apparatus is moving along the front of the spinning machine. The cutting also must be done while maintaining the yarn stationary with respect to a direction of the yarn traverse motion, i.e., allowing the yarn always to pass a fixed position, at which the yarn is to be cut, during the cutting.

With a prior automatic doffing apparatus, a yarn cutting mechanism has had a divergent yarn guide mounted thereon so that the yarn is adapted to be centrally guided by the divergent guide to be brought into a fixed position at which to be cut by the cutter. If it is assumed that the yarn is just in the fixed central position when the cutter is ready to cut the yarn, the cutting can be done with meeting the above requirements. However, assuming that the yarn is traversing in a direction away from the central fixed position when the yarn is ready to cut the yarn, the cutting cannot be carried out until the yarn reaches back the central fixed position. This means the cutting to be delayed and not to be done within the given short time, resulting in a disadvantage that the doffing apparatus does not operate in a required manner. In case where a fine count yarn is to be spun, the above disadvantage becomes more conspicuous because of lower spinning and traversing speeds of the fine count yarn.

SUMMARY OF THE INVENTION

It is accordingly an object of this invention to provide a device for biasing a yarn into a fixed position adapted for use with a yarn cutting mechanism of an automatic doffing apparatus, which device allows the yarn to be cut effectively and surely in a very short time without presenting any disadvantages peculiar to the prior art cutting mechanism of the automatic doffing apparatus.

The above and further objects of this invention can be achieved by providing a device for biasing a yarn into a fixed position for use with a yarn cutting mechanism of an automatic doffing apparatus, for doffing full packages one by one from a plurality of spinning units, arranged in side-by-side relation, of a spinning machinery while travelling along the front of the spinning ma-

chinery, the cutting mechanism being movable into a yarn cutting position to cut the yarn prior to doffing the corresponding full package; the yarn biasing device comprising a stationary divergent yarn guide disposed in the vicinity of a cutter section of the cutting mechanism and formed with a yarn restraining part, the yarn being guided to traverse along the divergent surface of the yarn guide when the cutting mechanism is brought into the yarn cutting position; and means for forcibly directing the yarn traversing along the yarn guide surface into the yarn restraining part when the yarn is to be cut, whereby the yarn is cut effectively and surely in a very short time.

BRIEF DESCRIPTION OF THE DRAWINGS

The invention will become more readily apparent from the following detailed description taken in conjunction with the accompanying drawings in which:

FIG. 1 is a side elevational view of an automatic doffing apparatus including a yarn cutting mechanism, which employs a device for biasing a yarn into a fixed position according to the invention;

FIG. 2 is a view explaining an operation of the yarn cutting mechanism of FIG. 1; and

FIG. 3 is a plan view of the yarn biasing device according to the invention, with a cutter removed.

DESCRIPTION OF THE PREFERRED EMBODIMENT

Referring to FIG. 1, there is shown, by way of example, a part of an open end spinning machine comprising a spinning unit 8, in which reference numeral S designates a spinning part including a feed roller, a fiber opening mechanism, a rotary spinning chamber, and a yarn outlet tube, by which a sliver F from a sliver can (not shown) is spun into a yarn 2; 34 a spun yarn take-up roller; 35 grooved traversing roller; 9 a bobbin holder holding a bobbin 4; and 10 a yarn package or cheese formed by winding the spun yarn 2 on the bobbin 4. As is known, the open end spinning machine generally comprises a plurality of the abovedescribed spinning units arranged in side-by-side relation.

The open end spinning machine further comprises an automatic doffing apparatus 1, which is designed such that it performs the operations of demounting the packages of a predetermined amount of spun yarn, i.e., the full packages 10, from the respective spinning units and mounting the empty bobbins 4 in the resultant vacancies automatically sequentially according to a predetermined program, while moving along the front of the open end spinning machine. For the purpose of performing the above operations, the main body of the doffing apparatus 1 comprises a yarn cutting mechanism 3 movable into a yarn cutting position shown by the imagination in FIG. 2 for cutting the yarn 2 prior to doffing; a rotary doffer 7 for demounting the full packages 10 from the bobbin holder 9 of the spinning machine and applying the empty bobbins 4 thereto by using a bobbin catcher 5 forming part of the rotary doffer; and an empty bobbin transmission mechanism 6 for transferring the empty bobbins 4 from an empty bobbin accommodating part (not shown) of the doffing apparatus to a predetermined position on a locus of the catcher 5 of the rotary doffer.

The detailed description of the yarn cutting mechanism 3 embodying the present invention will be made hereinafter; however, those of the bobbin catcher 5,

transmission mechanism 6 and rotary doffer 7 and a driving mechanism(s) therefor will be omitted since they are not concerned with the subject matter of this invention.

In general, the yarn cutting mechanism 3 with yarn suction means to be described latter serves to cut, prior to doffing, the spun yarn 2 extending to the package 10 and to suck successively thereafter the spun yarn 2 being delivered from the spinning part S towards the automatic doffer 7, while the package 10 is being doffed, so as to facilitate the lapping of the spun yarn 2 on the empty bobbin 4.

In FIGS. 1 - 3, the yarn cutting mechanism 3 according to the present invention is turnable, in the direction shown by the double-headed arrow, along with a pin 11 by driving a cam 13 which is, when driven, capable of oscillating a sector gear 14 engaging with a pinion means 12 mounted on the pin 11. The cutting mechanism 3 comprises a support 15 secured to the pin 11, which support has at one end a yarn suction nozzle 16 and a cutter 17 mounted thereon. The cutter 17 (not shown in FIG. 3) may be of a scissors type having a pair of yarn cutting blades mounted on a pin 18 for pivotal movement in opposite directions. On the pin 18 also mounted is a stationary yarn guide 19 consisting of a pair of slightly upwardly inclined arms with a yarn restraining part or a slit 20 formed therebetween for the purpose to be described latter. The slit 20 is formed such that the blades of the cutter 17 when in the closed or yarn cutting state are brought in side-by-side relation with the slit 20. Furthermore, the pin 18 has a pair of yarn forcing arms 21 and 22 turnably mounted thereon on the side of the yarn guide 19. The arms 21 and 22 operate to close and open, thereby forcibly directing the traversing yarn 2 into the slit 20. The forcing arms 21 and 22 intercross at the pin 18 and their lower ends are connected respectively to upper ends of a pair of links 23 and 24. Lower ends of the links 23 and 24 are connected by a common pin 26 to the free end of an operating rod 25, which is supported for sliding movement by supports or guides 27 and 28 attached to the support 15. The other end of the operating rod 25 is connected to a plunger 30 of a solenoid 29 which is, in turn, also secured to the support 15. The operating rod 25 is normally biased in such a direction as allowing the forcing arms 21 and 22 to open by a coil spring 32 disposed on the operating rod 25 between the guide 28 and a stop plate 31. Connected to the end of the support 15 remote from the suction nozzle 16 is a balance weight 33. This solenoid 29 may be common to the cutter 17 and the yarn forcing arms 21 and 22.

In operation, when it is desired to cut the yarn 2 leading to the package 10, the yarn cutting mechanism 3 is rotated counterclockwise from a phantom line position designated by a reference numeral 3" in FIG. 2 through the solid line position to a phantom line position designated by a reference numeral 3' in FIG. 2 and the head portion of the yarn cutting mechanism 3 is located in the yarn cutting position between the take-up roller 34 and the traversing roller 35. When the cutting mechanism 3 reaches this position, the solenoid 29 is excited one or more times in a known manner to retract the operating rod 25 against the action of the coil spring 32, whereby the yarn forcing arms 21 and 22 are rotated toward each other as shown by the imagination in FIG. 3 for each excitation of the solenoid 29. At this time, the yarn 2, which is now passing between the

blades of the cutter 17 while contacting with and traversing along the yarn guide 19 is forcibly brought into the slit 20 by the forcing arms 21 and 22 irrespective of the yarn traversing direction. Immediately thereafter

5 or substantially at the same time, the blades of the cutter 17 are operated by the solenoid 29 or by any other suitable means to pinch the yarn 2 passing through the slit 20, thus cutting the yarn at the fixed position. The cut end of the yarn leading to the traversing roller 35 10 is taken up by the package 10 and the other cut end of the yarn leading from the take-up roller 34 is sucked into the suction nozzle 16 in the known manner, so that the spun yarn 2 delivered from the spinning part 8 is 15 continuously sucked into the suction nozzle 16 as a cut yarn. Then, the cutting mechanism 3 is displaced from the position 3' to the phantom line position 3" of FIG. 2 under such condition.

With respect to the operations of the bobbin catcher 5, empty bobbin transmission mechanism 6 and rotary doffer 7, after the yarn 2 has been cut in the abovedescribed manner, first of all, a first package receiving and transporting plate 36 driven by a shaft 38, which also drives a second package receiving and transporting plate 37, lifts up the package 10 and the holder 11 from 20 a phantom line position to substantially a solid line position. At this time, the holder 11 is adapted to release the package 10 due to a not shown cam mounted on the shaft 38 and therefore the package 10 is allowed to drop on the first plate 36. Upon further driving of the shaft 38 and hence the first and second plates 36 and 37, the package 10 received by the first plate 36 is 25 transferred onto the second plate 37, by which the package 10 is transported onto a pivotable gutter 41. The gutter 41 is in communication with a package container (not shown) to feed the package 10 thereto. The bobbin catcher 5 is rotated with the first and second plates 36 and 37 by the shaft 38 and makes a circular motion shown by a phantom line in FIG. 1. The transmission mechanism 6 transfers the empty bobbin 4 to 30 a predetermined position on the locus of the bobbin catcher 5, allowing the empty bobbin 4 to be caught by the bobbin catcher 5. Then, the empty bobbin 4 is 35 fed to the bobbin holder 9 and held by the same.

According to this invention, when the cutting mechanism is ready to cut the yarn leading to the package 10 while contacting the surface of the yarn guide, the yarn is adapted to be forcibly quickly brought by the yarn forcing members 21 and 22 into the slit 20 centrally positioned in the yarn guide, so that the positive yarn cutting operation can be completed within the given short time even when the yarn is traversing in a direction away from the central slit 20. This enables the succeeding doffing and empty bobbin applying operations to have enough time.

55 What we claim is:

1. A device for biasing a yarn into a fixed position for use with a yarn cutting mechanism of an automatic doffing apparatus for doffing full packages one by one from a plurality of spinning units, arranged side-by-side, of a spinning machinery while travelling along the front of the spinning machinery, said cutting mechanism being movable into a yarn cutting position to cut the yarn prior to doffing the corresponding full package; said device comprising a divergent yarn guide disposed in the vicinity of a cutter of said cutting mechanism and formed with a yarn restraining part, the yarn being guided to traverse along the divergent surface of

said yarn guide when said cutting mechanism is brought into said yarn cutting position; and means for forcibly directing the yarn traversing along the yarn guide surface toward said yarn restraining part when the yarn is to be cut, whereby the yarn is cut effectively and surely always at the fixed position and in a very short time.

2. The device as set forth in claim 1, wherein said yarn guide is fixedly secured to a pin mounted on a support of said cutting mechanism for carrying a pair of blades of the cutter movable thereabout to open and close, said yarn restraining part being so located as to extend substantially in parallel to the cutter blades in the closed state.

3. The device as set forth in claim 2, wherein said yarn directing means comprises a pair of yarn forcing members turnably carried by said pin and, when it is desired to cut the yarn, said yarn forcing members turn toward each other to forcibly direct the yarn into said yarn restraining part.

4. The device as set forth in claim 1, wherein said yarn directing means is controlled by a solenoid.

5. The device as set forth in claim 4, wherein said solenoid also controls the opening and closing of the cutter.

6. The device as set forth in claim 1, wherein said yarn restraining part is an oblong slot.

7. A yarn cutting mechanism of an automatic doffing apparatus for doffing full packages one by one from a plurality of spinning units, arranged side-by-side, of a spinning machinery, while travelling along the front of the spinning machinery, said cutting mechanism comprising a support movable to bring said cutting mecha-

nism into a yarn cutting position; a cutter consisting of a pair of blades carried by said support for pivotal motion to close and open; a divergent yarn guide carried by said support and formed with a yarn restraining part 5 so arranged as to extend substantially in parallel to said blades in the closed state, said yarn guide being brought into contact with the yarn, when said cutting mechanism is in the yarn cutting position, to guide the yarn into said yarn restraining part; a solenoid carried by 10 said support to cause the pivotal motion of said blades; and a pair of arms carried by said support for pivotal motion to close and open, said arms forcibly and quickly directing, when they close, the yarn toward said 15 yarn restraining part, whereby the yarn is cut effectively and surely always at the fixed position and in a very short time.

8. A device for biasing a traversing yarn into a fixed position when the yarn is ready to be cut, comprising a divergent yarn guide movable, prior to cutting the 20 yarn, into contact with the yarn to allow it to traverse along the divergent surface of said yarn guide, said yarn guide being formed with a yarn restraining part by which the yarn is restrained when the traversing yarn reaches there, and means for forcibly directing the traversing yarn toward said yarn restraining part, said directing means movable integral with said yarn guide to approach to the traversing yarn and including a pair of 25 forcing arms turnable with respect to said yarn guide in opposite directions while forcibly directing the yarn toward said yarn restraining part.
